RADIATOR HOSE UNIT

Max I. Campbell, P.O. Box 1165,
Topeka, Kans. 66601

Filed Feb. 14, 1969, Ser. No. 15,777

Term of patent 14 years

Int. Cl. D23—01

U.S. Cl. D23—45

FIG. 1 is an elevational view of a radiator hose unit showing my new design;

FIG. 2 is an end elevational view thereof; and

FIG. 3 is a cross sectional view taken on line 3—3 of FIG. 1.

I claim:

The ornamental design for a radiator hose unit, as shown.
